H. W. McCULLOCH

NUT LOCK

Filed Jan. 26, 1921

Inventor
HAROLD W. McCULLOCH.

By his Attorney

W. J. Emissen

UNITED STATES PATENT OFFICE.

HAROLD WEED McCULLOCH, OF NEW YORK, N. Y.

NUT LOCK.

Application filed January 26, 1921. Serial No. 440,128.

To all whom it may concern:

Be it known that I, HAROLD WEED McCULLOCH, a citizen of the United States, residing at the city of New York, county of 5 Bronx, and State of New York, have invented new and useful Improvements in Nut Locks, of which the following is a specification.

My invention relates to improvements in 10 nut locks, and has for an object an increase in effectiveness of devices of this kind.

In preventing the loosening of nuts by turning due to jars, vibrations, etc., a common recourse is had to locking devices which 15 are interposed between the nut and the abutting face of the object against which the nut is to be screwed. Considerable annoyance is caused, when the nuts are being put on or taken off, to clamp and unclamp two 20 elements, by reason of the locking devices becoming lost or misplaced. An object of my invention is to provide a locking device which avoids danger of its loss or misplacement, and which is simple, reliable, durable 25 efficient and inexpensive. Other objects and advantages will be apparent from the following description, and the novel features of my invention will be particularly pointed out in the claim.

30 In carrying out my invention I provide the surface of one of the elements against which the nut abuts with one or more resilient nut engaging prongs which border the edge of the aperture through which the bolt carrying the nut passes. These prongs may 35 comprise resilient strips formed by striking them up from the element when the latter is of sheet material so as to present an end edge to the under face of the nut. One 40 or more of the prongs may be struck up from the portion of the sheet element bordering the bolt aperture or one single prong may be struck up, all extending from the interior of the sheet to the bolt aperture and 45 thereby partially around a portion of the aperture.

In the accompanying drawings, Fig. 1 is a respective illustrating one embodiment of my invention.

50 Fig. 2 is a plan of the same.

Fig. 3 is an elevation of two elements clamped by a nut and bolt and having my invention embodied therein.

55 Fig. 4 is a perspective illustrating another embodiment of my invention.

Fig. 5 is a plan of the same.

Fig. 6 is an elevation of the same.

Fig. 7 is a perspective illustrating another embodiment of my invention, and

Fig. 8 is a perspective illustrating still 60 another embodiment of my invention.

Referring now to the drawings, particularly Figures 1 to 5, the elements 1 and 2 are clamped together by means of a bolt 3 passing through apertures 4 in the elements 65 and carrying a nut 5. The element 1 is formed of sheet resilient metal and preferably of metal which can be hardened. In the embodiment of Figs. 1 to 3 one or more prongs 6 are struck up from the portion of the sheet bordering the aperture, one side of each prong being coincident with a portion of the edge of the aperture. The ends of the prongs project upwardly at an angle to the face of the element so as to present the 70 sharp end corner edges to the under face of the nut, and by their resilient engagement with the nut they will act somewhat like the well known split washer and lock the nut against accidental loosening such as 75 may be due to jars, vibrations, etc.

In Figs. 4 to 6, which illustrate an embodiment of the invention to which the claim is directed, the element 1 is provided with but one single prong 7, of greater length than 80 the prongs 6, which prong extends from the interior of the element to the aperture 4 and then around the major portion of the edge of the aperture with an upwardly turned end so as to present the sharp end corner 85 edge to the under face of a nut. This prong in this embodiment is also struck out of the element by stamping with a shearing die, and the prong gradually rises from the element 1 toward the free end so as to provide 90 resiliency and press against the under side of the nut to lock it when it is screwed down.

Having described my invention, what I claim is:

A sheet element having an aperture there- 100 in through which a threaded stem may pass, and also having a struck up resilient nut en- gaging prong extending from the interior of the sheet to the aperture and there around a portion of the edge of the aperture. 105

In testimony whereof I have hereunto set my hand.

HAROLD WEED McCULLOCH.
